UNITED STATES PATENT OFFICE.

DAVID L. LINDQUIST AND DAVID LARSON, OF YONKERS, NEW YORK, ASSIGNEES TO
OTIS ELEVATOR COMPANY, OF JERSEY CITY, NEW JERSEY, A CORPORATION OF
NEW JERSEY.

SLACK-CABLE DEVICE.

1,148,240.

Specification of Letters Patent. Patented July 27, 1915.

Application filed March 3, 1911. Serial No. 612,080.

To all whom it may concern:

Be it known that we, DAVID L. LINDQUIST and DAVID LARSON, subjects of the King of Sweden, residing at Yonkers, in the county 5 of Westchester and State of New York, have invented a new and useful Improvement in Slack-Cable Devices, of which the following is a specification.

Our invention relates to the class of safety 10 appliances commonly known as slack cable devices, adapted for use in connection with traction elevators, hoisting mechanism and the like.

The invention comprises an electric switch 15 and means for operating the switch located in position to be actuated by slack in a hoisting cable.

An object of the invention is to provide 20 simple and reliable mechanism of this character, the same being inclosed in a protecting casing designed to permit ready access to the inclosed mechanism.

Other objects of the invention, and the 25 exact nature thereof, will appear more fully hereinafter.

In the accompanying drawings which illustrate a construction embodying the invention, Figure 1 is a side elevation view of the mechanism, the casing being shown in 30 section; Fig. 2 is a front elevation of the same, the cover section of the casing being removed.

The casing comprises a stationary section 1 which is preferably made of cast iron and 35 may have cast integral therewith brackets 3 and 4, adapting it to be secured to any suitable base or support. A cover section 2 is removably secured to the main section 1 by bolts 5. Within the casing is an electric 40 switch comprising a switch arm 6 mounted on pivot shaft 7 having bearings in the casing or in brackets 8 formed integral with the casing. This switch arm carries switch contacts 9 secured to the ends of leaf springs 45

10. The latter may be attached to the switch arm by means of a bolt 11. This bolt and the springs 10 carrying the contacts 9 are insulated from the switch arm by means of a bushing 12 made of any suitable insulating material. Stationary contacts 13 are carried by the bracket arms 14. The contacts 13 are formed on the ends of rods or stems 15 which extend through the brackets 14 and are insulated therefrom by means of bushings 16. The outer ends of the stems

15 are screwthreaded and together with the clamping nuts 17 form binding posts to which the conductors are attached. The conductors are led into the casing through an inlet pipe 18 which may be threaded into 60 an opening in the casing.

Extending through the casing near its upper end and journaled therein is a shaft 20 to which is keyed an arm 21 carrying an anti-friction roller 22 in contact with the switch arm 6. The shaft 20 extends beyond the sides of the casing and has keyed thereto weights 23 located outside the casing. Each of these weights is formed with an extension 24 to which is riveted or otherwise secured an arm 25. A cross-piece 26 extends between these arms and is secured to the latter and has its ends turned up to form extensions 27.

When the safety device is used in connection with a traction elevator or other hoisting mechanism, it is secured in position with the cross bar 26 beneath and in close proximity to the hoisting drum. The parts are normally in the relative position indicated in the drawings. In this position the arm 21 holds the switch closed. A coil spring 28 is located in a pocket or recess 29 formed in the casing or a block 30 formed integral with the casing. This spring tends 80 to move the switch arm 6 upwardly but such movement is resisted by the arm 21.

If now the hoisting cable becomes slack, it will engage the cross strip 26 and move the latter downward swinging the arm 21 to the 90 right, and carrying the roller 22 into a recess 23'. The switch arm 6 is now free and is swung open by the spring 28, separating the switch contacts 9 and 13. The weights 23 which normally hold the locking arm 21 in 95 the position shown, are carried upward and to the left as the shaft rotates, and their effective weight gradually reduced. If the spring 28 should, for any reason, fail to operate, the roller 22 would be brought into contact with a projection 30 carried by the switch lever and swing the latter to open position independently of the spring. This operation might also take place in conjunction with the spring and assist the latter in opening the switch. It will thus be seen that the locking arm 21 not only acts as a locking device to hold the switch closed and permit it to be opened by the spring when the said arm is operated, but also forms a 110

positive means adapted to open the switch independently of the spring 28.

It will be observed that the switch contacts and binding posts extend beyond the 5 main portion 1 of the casing and are located in the cover portion 2, so that when the latter is removed the switch mechanism is entirely exposed and readily accessible for adjustment or repairs. Removable screw 10 plugs 31 may be provided in the sides of the casing to permit access to the switch independently of the removable cover.

We wish not to be limited to the particular construction herein disclosed, as various 15 modifications might be made without departing from the spirit and scope of the invention.

What we claim as new and desire to secure by Letters Patent of the United States 20 is:

1. In combination, a casing, a switch located therein and comprising a movable switch arm, a rock-shaft extending through the casing, a locking arm carried by said 25 shaft, and movable into position to lock the switch arm in closed position, weights secured to the ends of the rock-shaft externally of the casing and in position to hold the locking arm in locking position, and a 30 frame carried by the rock shaft for operating the latter.

2. In a slack cable device, the combination of a casing, a switch located therein and comprising a pivoted switch arm, a switch 35 opening spring, a rock shaft extending through the casing, a locking arm carried by said shaft in position to lock the switch arm in closed position, a projection carried by the switch arm in the path of said locking arm, arms secured to the ends of the rock shaft outside the casing, a cross bar connecting said arms, and a weight carried by the rock shaft in position to hold the locking arm in locking position.

45 3. In a slack cable device, the combination

of a casing, a switch located therein and comprising a pivoted switch arm, a spring for moving said arm to open position, a rock shaft extending through the casing, an arm operable by said shaft in position to lock the switch arm in closed position, and engageable with the switch arm positively to move the same to open position, and a recess in said switch arm co-acting with said locking arm when the latter is in locking position and adapted to offer resistance to the movement of the said locking arm to unlocking position.

4. In a slack cable device, the combination of a casing, a switch located therein and comprising a pivoted switch arm, a spring for moving said arm to open position, a rock shaft extending through the casing, an arm operated by said shaft to lock the switch arm in closed position, means carried by the switch arm coacting with said shaft and arm positively to move the switch arm to open position, and a recess in said switch arm co-acting with said locking arm when the latter is in locking position and adapted to offer resistance to the movement of the said locking arm to unlocking position.

5. In combination, a switch comprising a movable switch arm, a rock shaft, a locking 75 arm carried by said shaft, and movable into position to lock the switch arm in closed position, weights secured to the ends of the rock shaft and in position to hold the locking arm in locking position, and a frame 80 carried by the rock shaft for operating the latter.

In testimony whereof we have signed our names to this specification in the presence of two subscribing witnesses.

DAVID L. LINDQUIST.
DAVID LARSON.
